UNITED STATES PATENT OFFICE.

WILLIAM F. HIRSCHMANN, OF NEW YORK, N. Y.

DESIGN FOR A BASE-BALL EMBLEM.

47,488.

Specification for Design.

Patented June 22, 1915.

Application filed March 17, 1915. Serial No. 15,087. Term of patent 7 years.

To all whom it may concern:

Be it known that I, WILLIAM F. HIRSCHMANN, a citizen of the United States, residing at New York, in the county of New York and State of New York, have invented a new, original, and ornamental Design for a Base-Ball Emblem, of which the following is a specification, reference being had to the accompanying drawing, forming part thereof.

The figure is a plan view of the emblem showing my new design.

I claim:

The ornamental design for a base-ball emblem, as shown.

WILLIAM F. HIRSCHMANN.

Witnesses:

CHARLES A. SCHWARZ,
HARRY L. LEVERETT.
